UNITED STATES PATENT OFFICE.

HENRY SCHERER, OF BILLINGS, MONTANA.

ELECTRIC-BULB HOLDER.

1,151,219.

Specification of Letters Patent. Patented Aug. 24, 1915.

Application filed March 25, 1915. Serial No. 16,987.

To all whom it may concern:

Be it known that I, HENRY SCHERER, residing at Billings, in the county of Yellowstone and State of Montana, have invented 5 a new and Improved Electric-Bulb Holder, of which the following is a specification.

This invention relates to that class of holders especially designed for use in connection with electric lamp bulbs and it has 10 for its object to provide a holder for the purpose stated of a simple and inexpensive construction, that can be readily applied for use in connection with the ordinary types of electric lamp bulbs and which effectively 15 serves its intended purpose.

My invention also has for its object to provide a holder of the character stated in which the main or body portion is composed of a spring wire strand bent to shape for 20 clamping the lamp socket and for supporting the bulb so as to keep it from jarring loose and in its attached connection with the socket.

With other objects in view, that will hereinafter appear, my invention consists of a 25 lamp holder that embodies the peculiar features of construction and arrangement of the parts hereinafter described, specifically pointed out in the appended claims and 30 illustrated in the accompanying drawing, in which:

Figure 1 is a side elevation of my holder applied for use. Fig. 2 is an end elevation of the same as applied for use. Fig. 3 is a 35 perspective view of the same detached from the lamp.

My improved holder comprises a main or body portion bent to shape from a single strand of spring wire and a bolt and nut for 40 clamping the holder onto the lamp socket.

The holder includes an open ring portion 1, the free end of which is bent to form an eye 2 and the other or opposite end of which also terminates in an eye 3 that opposes the 45 eye 2, and together with the said eye 3 is adapted for receiving a bolt 4 that carries a nut 5, that clamps the ring portion 1 about the socket 6 when the holder is applied for use, as shown in Figs. 1 and 2 of the drawings.

7 designates the hanger portion of the

holder formed by bending the wire strand downwardly from the eye 3, and the said portion, in practice, is of a length to extend down to the lower end of the bulb, and the 55 lower end of the said portion is bent to form a coil 8 and then inwardly at right angles to form a supporting member 9, the end of which is bent into a coil 10 to provide a seat for engaging the lower end of the bulb 11. 60

By reason of the peculiar formation of my spring wire lamp holder, the same can be quickly applied to or removed from the lamp socket and the bulb, by proper adjustment of the nut 5 on the clamp bolt 4 and by bending 65 down the member 9 from engagement with the lamp bulb, it being understood the coil 8 on the wire puts the required tension on the member 9 to keep the lamp from jarring loose in the socket and from vibration. 70

The spring coil 8 can be used for hanging up the lamp.

From the foregoing taken in connection with the drawing, the complete construction, the advantages of and the manner in which 75 the holder may be applied for use will be readily apparent.

While the construction of the holder shown is a preferred form it is particularly understood that changes in size, proportion 80 and minor details thereof may be made without departing from my invention and which may come without the scope of the appended claims.

What I claim is:

1. A lamp holder formed of spring wire comprising an open ended ring portion provided with opposing eye members, a bolt and nut for coöperating with the said eye members for clamping the ring portion on 90 a lamp socket, a member pendent from the ring portion bent at the lower end to form a spring coil, and an inwardly projecting portion, said projecting portion terminating in a coil that forms a seat for receiving the 95 lower end of a lamp bulb, the axis of said spring coil lying in a plane at right angles to the plane of that of the axis of the seat coil.

2. The combination with a lamp socket 100 and bulb; of a spring wire holding device, one end of which is bent to form an open

ended ring, the opposing ends of the said ring portion terminating in coils, a bolt for engaging the coils, a clamp nut on the bolt for drawing the ends of the ring portion together, a member pendent from one of the coils of the ring portion whose lower end is bent to form a spring coil and terminates in an arm that projects inwardly at right

angles to the pendent member and whose end terminates in a coil for engaging with 10 the lower end of the lamp bulb.

HENRY SCHERER.
